UNITED STATES PATENT OFFICE.

FRANK C. APPLEBY, OF PITTSBURGH, PENNSYLVANIA.

SLIP-SHEET-FEEDING ATTACHMENT FOR PRINTING PRESSES.

1,403,371.

Specification of Letters Patent. Patented Jan. 10, 1922.

Continuation of application Serial No. 363,493, filed March 5, 1920. This application filed December 22, 1920. Serial No. 432,425.

To all whom it may concern:

Be it known that I, FRANK C. APPLEBY, a resident of Pittsburgh, in the county of Allegheny and State of Pennsylvania, have invented a new and useful Improvement in Slip-Sheet-Feeding Attachments for Printing Presses, of which the following is a specification.

The invention relates to printing presses, and has particularly to do with presses for printing sheets of different sizes, and which are provided with mechanism coordinated with the operation of the press for feeding sheets successively from a stock table to the press platen and from the platen to a receiving table. The object of the invention is to provide improved means, coordinated with the operation of the printing press, for feeding slip sheets between the printed sheets placed on the receiving table.

The invention is illustrated in the accompanying drawings, of which Fig. 1 is a side view of the printing press feeding mechanism; Fig. 2 a partial plan view thereof; Fig. 3 a vertical sectional view taken substantially on the line III—III, Fig. 2; and Figs. 4, 5 and 6 sectional views of details of construction to enlarged scale, the planes of view being taken, respectively, on the lines IV—IV, V—V and VI—VI, Fig. 2.

Since the slip-sheet feeding mechanism shown herein as illustrative of the invention is coordinated with the mechanism for feeding sheets to a platen and for removing sheets from the platen to a receiving table, the general arrangement and operation of such sheet-feeding and removing mechanism will be first explained.

The sheet-feeding mechanism is shown as applied to a Gordon type printing press of well known form. The frame 1 of the press is provided with a vertically movable stock table 2 for supporting a pile 3 of blank sheets, which are successively fed to a platen 4. The feeding of the sheets involves two operations, first, raising the edge of the top sheet from the pile, and second, engaging the edge of the raised sheet and moving the sheet upon the platen. For raising the top sheet, there is provided a bar 5 extending over the top of the pile 3, and to such bar there are attached a plurality of shoes 6 provided with internal chambers which are in communication with a suction line 7 extending to a suitable fan or air pump, not

shown. The bottom of the shoes are provided with openings, so that, when the shoes are caused to bear upon the top sheet of the pile, such sheet will adhere to the shoes. For vertically reciprocating the bar 5, it is attached to the outer ends of levers 9 by means of rods 8, the other ends of which levers are pivoted to a supporting rod 10. The levers 9 are, by means of a spring 11, held yieldingly upwardly against a cam 12 attached to a shaft 13 adapted to have one complete revolution during each cycle of operation of the press.

In the position of the parts shown in Fig. 3, the cam 12 has pressed the levers 9 downwardly, and in consequence thereof the bar 5 holds its attached shoes 6 against the top sheet of the pile 3. After a sheet has been raised from the pile 6, it is picked up by gripper fingers 16 attached to a frame 14, which frame is moved by means of the rack 15 to cause the sheet to be placed upon the platen 4, the details and manner of operation of which parts are well known to those skilled in the art.

Above the stock table 2 there is a second table 16 for receiving the printed sheets, and means are provided, in coordination with the operation of the press, to remove the printed sheets from the platen and place them on the receiving table. The means to this end include a plurality of pairs of resilient sheet-engaging fingers 17 attached to housings 18 carried by, and adjustable longitudinally of, a pair of rods 19 and 20. The rod 20 is supported by a sleeve 21 secured to the upper end of an arm 22, pivoted to the press frame at 23 and adapted to be oscillated by mechanism presently to be explained. Normally, the engaging fingers 17 are closed, means being provided to open them when the arm 22 has been oscillated to a position in which the fingers may engage a printed sheet. Mechanism is also provided for raising the forward ends of the sheet-engaging or gripper fingers 17, so that a sheet of paper on the platen may be readily engaged by them. The apparatus for oscillating the arm 22, for opening the gripper fingers 17, and for raising the forward ends of the grippers, will now be explained in the order stated.

For oscillating the arm 22 a segmental gear 24 is attached to such arm and meshes with a similar gear 25 attached to an arm 110

26 pivoted to the press frame at 27. The arm 26 is provided with a lateral projection or roller 28 engaged by a slot cam 29 secured to the shaft 13, the cam being so formed that the arm 22 passes through a complete cycle of oscillation upon each rotation of the shaft 13. To adjust the position of the arm 22 so that the gripper fingers may be moved to various positions 10 on the press platen, the segmental pinion 24 is provided with an arm 30, at the end of which there is a pin 31 extending into a slot 32 formed in a downwardly extending projection of the arm 22. A set-screw 33 is provided for fixing the position of the pin 31 in the slot 32. By adjusting the set-screw the arm 22 may be moved towards or from the perpendicular, it being understood that the segmental pinion 24 is pivoted 20 on the axis 23, and that the segmental pinion 25 is, when the mechanism is not in operation, held in fixed position by the slot cam 29.

For opening the gripper fingers 17, the rod 20 is provided with segmental pinions 34 (Fig. 3) which mesh with racks 35, longitudinally movable in the housings 18, and having attached to their ends wedging members 36. To move the segmental pinions 34 for this purpose the rod 20 is rotated by means of a vertically movable bar 36 carried by the arm 22 and attached at its upper end to the rod 20 by means of a crank arm 37. The bar 36 is normally held downwardly by means of a spring 38 acting between the rod and the arm 22. The lower end of this bar is pivotally attached to the outer end of an arm 39 pivoted to the press frame at 40, which arm is provided with laterally extending fingers 41 and 42 adapted to strike stops 43 and 44, respectively, when the arm 22 approaches the ends of its oscillating movements.

For raising the rod 19 to elevate the forward ends of the gripper fingers 17, such rod is secured to an arm 45 pivotally supported at one end by the rod 20. The other end of the arm 45 is turned laterally and pivotally attached to the upper end of a bar 46 carried by the oscillating arm 22 and held normally downwardly by means of a spring 47. The lower end of the bar 46 is provided with a roller 48 adapted to ride upon a curved guide bar 49 pivoted at 50 to the arm 22. The outer end of the guide bar is provided with a slot 51 engaged by an arm 52 of a bell crank lever pivoted to the press frame at 53 and having a second arm 54 bearing at its outer end upon the face of a cam 55 secured to the shaft 13. The cam 55 is provided with a projection 56 which causes the arm 54 to move outwardly and hence to raise the guide 49 when the oscillating arm 22 approaches the platen.

65 In the drawings the several parts of the

mechanism for removing sheets from the platen and depositing them upon the receiving table 16 are indicated in an intermediate position. In operation, the rotation of the shaft 13 causes the arm 22 to swing forwardly, the driving connections for such movement including the slot cam 29, pivoted arm 26 and segmental pinions 25 and 24. As the arm 22 approaches its extreme forward position, the projection 56 of cam 55 causes the bell crank lever 54, 52 to elevate the guide 49, and as a result thereof the bar 46 is raised against the tension of spring 47. Such raising of the bar 46 causes the rod 19 to swing upwardly and outwardly upon the rod 20 with a result that the forward ends of the gripper fingers 17 are brought to a position in which they may readily engage a printed sheet. Also, when the arm 22 approaches its forward movement, the finger 42 of the pivoted arm 39 strikes the stop 44 and causes the pivoted arm 39 and the longitudinally movable bar 36 attached to it to move downwardly, with the result that the rod 20 is rotated to cause the wedges 36 to open the gripper fingers 17. When the arm 22 begins its backward oscillation, the finger 42 moves from the stop 44 and the spring 38 causes the bar 46 to move downwardly so that the gripper fingers may close upon the sheet between them. During the beginning of the backward movement of arm 22 the press platen moves in the same direction so that the sheet remains in the grippers 17 until they are closed. As the arm 22 approaches the end of its backward oscillation, the finger 41 engaged the stop 43 with the result that the gripper fingers are opened to permit the engaged sheet to fall upon the receiving table 16. This completes the cycle of operation which is repeated for each cycle of operation of the press.

While the present invention may be used with various forms of sheet-feeding and removing mechanism, it is preferably used with the mechanism shown herein and just described. For feeding slip sheets between the printed sheets, there is provided a slip-sheet table, means for separating the slip sheets successively from a pile thereof, and means for transferring the slip sheets from the slip-sheet table to the receiving table.

The slip-sheet table, indicated at 60, is preferably attached by means of arms 61 to the vertical movable stock table 2, so that, as the stock table is raised to bring the pile of blank sheets against the shoes 6, the slip-sheet table will be similarly raised. The slip sheets are preferably successively separated from a pile 62 thereof by raising the edge of the upper sheet. For this purpose there is preferably provided suction mechanism similar to that used in the sheet-feeding mechanism described above. Such 130

section mechanism, as shown in the illustrative embodiment of the invention, comprises a horizontally disposed bar 63 to which there are adjustably attached a plurality of suction shoes 64. As seen in Figs. 5 and 6, each shoe is provided interiorly with a chamber 65, the lower wall of which is provided with perforations 66. The chambers 65 communicate with a flexible branch air line 67 extending from the main suction line or conduit 68, which later communicates with a suitable air pump or fan. For adjusting the shoes 64 upon the bar 63, such bar may be provided with a plurality of recesses 69, and each shoe may be provided with a spring-pressed rod 70. By moving the rod 70 outwardly, the shoe may be slid along the bar 63 to any desired position and locked in such position by releasing the rod 70 to permit its inner end to engage one of the recesses 69.

The vertical reciprocation of the bar 63 is affected simultaneously with the vertical reciprocation of the bar 5 of the sheet-feeding mechanism. In the illustrative embodiment of the invention, this is accomplished by connecting the bars 5 and 63 to each other by means of arms 71, which are suitably guided by the press frame to cause them to properly rise and fall with the bar 5. Thus, each time a sheet is raised from the stock pile 3, a sheet is also raised from the slip-sheet pile 62.

For transferring sheets from the slip-sheet pile to the receiving table 16, gripper fingers are preferably adjustably attached to the rods 19 and 20. As particularly illustrated in Fig. 4, each pair of gripper fingers may comprise a frame 72, provided at its end with a finger 73, and having pivoted to it, as at 74, a second finger 75. Each finger 75 is urged upwardly by means of a spring 76, and is normally held closed upon the finger 73 by means of a tongue or wedge 77 provided with a rack 78 which meshes with a segmental pinion 79 attached to the rod 20. Thus, when the rod 20 is rotated to open the gripper fingers 17 to release a sheet being carried from the platen, the tongue 77 is moved away from the pivot point 74 to permit the finger 75 to rise and thereby permit a slip-sheet to enter between it and the finger 73. On the forward oscillation of the arm 22 the slip-sheet is carried by the pairs of gripper fingers 73, 75, and is released therefrom and permitted to fall upon the last printed sheet received by the receiving table 16, the gripper fingers 75 being permitted to be opened by the springs 76 when the rod 20 is rotated to cause the gripper fingers 17 to open to engage a sheet upon the platen 4.

The operation of the mechanism for removing sheets from the platen and placing them upon the receiving table has already

been explained. When the arm 22 approaches the end of its backward stroke the downward movement of the bar 26 caused by the finger 41 striking the stop 43 opens the fingers 73, 75, simultaneously with the opening of the fingers or grippers 17. The fingers 73, 75 at this time engage a slip-sheet which is raised from the top of the pile 62, and the finger 17 releases the printed sheet so that it may fall upon the receiving table 16. When the arm 22 moves forwardly, the finger 75 closes upon the finger 73 and thereby grips the slip-sheet which is carried from the slip-sheet table to the receiving table. This slip-sheet is dropped from the fingers 73, 75 when the fingers 17 are open to receive a sheet from the platen. The general result is that printed and slip-sheets are placed in alternation upon the receiving table 16.

This application is a continuation of my pending application, Serial No. 363,493, filed March 5, 1920.

According to the provisions of the patent statutes, I have described the principle and operation of my invention together with the construction which I now consider to represent the best embodiment thereof. However, I desire to have it understood that within the scope of the appended claims, the invention may be practiced by other forms of construction not particularly shown and described.

I claim:

1. In a printing press, the combination with a stock table, a platen, a receiving table, and coordinated mechanism for feeding sheets successively from the stock table to the platen and from the latter to the receiving table; of a slip-sheet table, means coordinated with said mechanism for successively raising sheets from the slip-sheet table, and means attached to and movable by said mechanism for engaging a raised sheet and transferring it to said receiving table in alternation with each printed sheet placed upon the receiving table by said mechanism.

2. In a printing press, the combination with a stock table, a platen, a receiving table, and coordinated mechanism for feeding sheets successively from the stock table to the platen and from the latter to the receiving table; of a slip-sheet table, means coordinated with said mechanism for successively raising sheets from the slip-sheet table, and gripper fingers attached to and movable by said mechanism for engaging a raised sheet and transferring it to said receiving table in alternation with each printed sheet placed upon the receiving table by said mechanism.

3. In a printing press, the combination with a stock table, a platen, a receiving table, and coordinated mechanism for feeding

- sheets successively from the stock table to the platen and from the latter to the receiving table; of a slip-sheet table, suction shoes movable in coordination with said feeding mechanism to successively raise sheets from the slip-sheet table, and gripper fingers movable by said feeding mechanism to engage a raised sheet and transfer it to said receiving table.
- 10 4. In a printing press, the combination of a vertically movable stock table, means including a vertically movable member for successively raising sheets from the stock table, a slip-sheet table, means attached to and movable by said member for successively raising sheets from the slip-sheet table, a platen, means for transferring sheets from the stock table to the platen, a receiving table, and an oscillating arm provided with means operative when said arm is moved in one direction to transfer a sheet from the platen to the receiving table and operative when the arm is moved in the opposite direction to transfer a sheet from the slip-sheet table to the receiving table.
- 15 5. In a printing press the combination with a stock table, a platen, a receiving table, and means for transferring sheets from the stock table to the platen; of a slip-sheet table, an oscillating arm, gripper fingers attached to and projecting from opposite sides of said arm, and means for causing the gripper fingers on one side of said arm to transfer a sheet from said platen to the receiving table during one stroke of the arm
- 20 and for causing the gripper fingers on the other side of said arm to transfer a sheet from the slip-sheet table to the receiving table during the opposite stroke of said arm.
- 25 6. In a printing press, the combination with a vertically movable stock table, a platen, a receiving table, and coordinated mechanism for feeding sheets successively from the stock table to the platen and from the latter to the receiving table; of a slip-sheet table attached to and vertically movable with said stock table, means movable in coordination with said feeding mechanism to successively raise sheets from the slip-sheet table, and means movable by said feeding mechanism to engage a raised sheet and transfer it to said receiving table.
- 30 7. In a printing press, the combination of a stock table, a slip-sheet table, means for successively separating sheets from the slip-sheet table, a platen, means for transferring sheets from the stock table to the platen, a receiving table, and an oscillating arm provided with means operative when said arm is moved in one direction to transfer a sheet from the platen to the receiving table and operative when the arm is moved in the opposite direction to transfer separated sheets from the slip-sheet table to the receiving table.
- 35 In testimony whereof, I have hereunto set my hand.

FRANK C. APPLEBY.

Witness:

EDWIN O. JOHNS.
